(57) **CLAIM**

The ornamental design for a meat thermometer with a wireless probe, as shown and described.

DESCRIPTION

1. Meat thermometer with a wireless probe

1.1 : Perspective

1.2 : Perspective

1.3 : Front

1.4 : Back

1.5 : Left

1.6 : Right

1.7 : Top

1.8 : Bottom

1.9 : Enlarged

1.10 : Exploded

The broken lines depict portions of the meat thermometer with a wireless probe that form no part of the claimed design; reproduction 1.9 is an enlarged view of a portion labeled "9" in reproduction 1.1; the dash-dot-dash lines in the reproductions and the number "9" in reproduction 1.1 are for the purpose of depicting the cut line of the enlarged view that form no part of the claimed design.
